UNITED STATES PATENT OFFICE

101,800

DESIGN FOR A FLASHLIGHT HEAD

Emerson H. Tompkins, Waterbury, Conn.

Application February 28, 1936, Serial No. 61,408

Term of patent 14 years

To all whom it may concern:

Be it known that I, Emerson H. Tompkins, a citizen of the United States and residing at Waterbury, in the county of New Haven and State of Connecticut, have invented a new, original, and ornamental Design for Flashlight Heads, of which the following is a specification, reference being had to the accompanying drawing, forming part thereof.

Fig. 1 is a top view of the ornamental flashlight head showing my new design.

Fig. 2 is a side view of the same.

The essential characteristics of my design consist primarily in the short top and bottom vertical necks, the pear shaped central body, the abrupt shoulder between the top vertical neck and the body, and the substantially cylindrical bottom section of said body adjacent said bottom neck, combined harmoniously with the flat top lens.

I claim:

The ornamental design for a flashlight head as shown and described.

EMERSON H. TOMPKINS.
